(57) **CLAIM**

The ornamental design for a fender for electric vehicle, as shown and described.

DESCRIPTION

FIG. 1 is a top, right side perspective view of the new design for a fender for electric vehicle, showing an illustration of use on an electric vehicle;

FIG. 2 is another top, right side perspective view thereof, with the exemplary electric vehicle removed for clarity of details;

FIG. 3 is a top, left side perspective view thereof;

FIG. 4 is a bottom, right side perspective view thereof;

FIG. 5 is a left side view thereof;

FIG. 6 is a right side view thereof;

FIG. 7 is a front view thereof;

FIG. 8 is a rear view thereof;

FIG. 9 is a top view thereof; and,

FIG. 10 is a bottom view thereof.

The broken lines shown in the drawings illustrate environment and portions of the fender for electric vehicle that form no part of the claimed design.

The shading lines shown in the drawings represent the approximate three-dimensional contour of the design, and are not intended to indicate surface decoration.
